(57) **CLAIM**

The ornamental design for a fishing reel body, as shown and described.

DESCRIPTION

FIG. 1 is front elevational view of a reel showing our new design.

FIG. 2 is a rear elevational view of the embodiment of FIG. 1. FIG. 3 is a left side elevational view of the embodiment of FIG. 1.

FIG. 4 is a right side elevational view of the embodiment of FIG. 1.

FIG. 5 is a top plan view of the embodiment of FIG. 1; and, FIG. 6 is a bottom plan view of the embodiment of FIG. 1. The broken line showing of environment in the drawings is included for the purpose of illustrating only and forms no part of the claimed design.
